B. F. SCIFORD.

APPARATUS FOR CARRYING SUBMARINE TORPEDOES.

APPLICATION FILED OCT. 3, 1917.

1,257,747.

Patented Feb. 26, 1918.

Inventor,

Benjamin F. Seiford,
By Frank L. Anderson.

UNITED STATES PATENT OFFICE.

BENJAMIN F. SCIFORD, OF EAGLE BUTTE, SOUTH DAKOTA.

APPARATUS FOR CARRYING SUBMARINE TORPEDOES.

1,257,747.

Specification of Letters Patent. Patented Feb. 26, 1918.

Application filed October 3, 1917. Serial No. 194,555.

To all whom it may concern:

Be it known that I, BENJAMIN F. SCIFORD, a citizen of the United States of America, and resident of Eagle Butte, in the county 5 of Ziebach and State of South Dakota, have invented certain new and useful Improvements in Apparatus for Carrying Submarine Torpedoes, of which the following is a specification.

10 This invention relates to apparatus for carrying submarine torpedoes and particularly to means for suspending the same and carrying them at the sides of a ship, means being also provided whereby the carrying 15 means may be manipulated in a novel manner for moving the torpedo holder to a position where another torpedo may be placed on the holder and whereby a repetition of the operation may be had.

20 A further object of this invention is to provide novel means for rigidly retaining the torpedo holder, provision being made for releasing the same upon impact of the 25 torpedo with an object and for thereafter resiliently retaining the torpedo holder in operative relation to the object which caused the disruption of the first mentioned retaining means.

A still further object of this invention is 30 to provide novel means whereby a torpedo holder may be moved vertically and oscillated so that it will assume practically a horizontal position where the holder will be accessible for replacing new torpedoes.

35 With the foregoing and other objects in view, the invention consists in the details of construction and in the arrangement and combination of parts to be hereinafter more fully set forth and claimed.

40 In describing the invention in detail, reference will be had to the accompanying drawings forming part of this specification wherein like characters denote corresponding parts in the several views, and in 45 which—

Figure 1 illustrates a view in elevation of a hull of a ship showing the torpedo holder embodying the invention applied thereto;

Fig. 2 illustrates a view in elevation of 50 the operating mechanism;

Fig. 3 illustrates a sectional view on the line 3—3 of Fig. 2; and

Fig. 4 illustrates a detail view showing 55 the manner of connecting the housing to the gearing.

Fig. 5 illustrates a detail view partly in section, showing the connection between the torpedo holder and rack bar.

In these drawings 5 denotes a suitable base which may be attached to a hull of a ship in 60 any preferred way, the said base having a shaft 6 journaled in it and the said shaft carrying a gear wheel 7 which meshes with a gear wheel 8 mounted on the shaft 9 carried by the base. The gear wheel 8 has an 65 arm 10 with an aperture 11 therein on which a shaft 12 is journaled, the said shaft being provided with a pinion 13 for a purpose to be presently explained. The base has a curved slot 14 through which the shaft 12 70 extends and in which it may move. The shaft 12 has a crank handle 15 applied to it so that it may be turned to rotate the pinion or the said crank handle may also be applied to the shaft 6 for the purpose of 75 rotating it as will presently appear.

The gear wheel 8 carries a housing or guide 16 which has a slot or aperture 17 in one edge, into which the teeth of the pinion 13 project as said pinion is rotated. The 80 teeth of the gear wheel 7 mesh with the teeth of the gear wheel 8 and when the gear wheel 7 is rotated through the manipulation or operation of the shaft 6, the gear wheel 8 will turn and motion will be communicated to 85 the housing and parts associated with it.

A rack bar 18 is slidable in the housing 16 and its lower end is provided with a socket 19 in which the torpedo holder 20 is attached by pins or other fastenings 21. 90 The torpedo holder may be of any construction which will hold the torpedo 22 but in practice a small encircling band fitting around the torpedo and clamped thereon has been found sufficient.

The pinion 13 engages the teeth of the rack bar 18 and therefore the rack bar may be elevated or lowered by turning the pinion 13.

A link 23 is pivotally mounted on the 100 base by the pin 24 and the opposite end of the link is forked so that it embraces the edge of the rack bar near its upper edge and the peg 25 preferably of wood extends through the bifurcated end of the link 105 and through the rack bar so that the rack bar is held rigid in a vertical position until such time as an obstruction is encountered by the torpedo and when that occurs the peg is sheared and the rack bar 110

and torpedo carrier yields and swings from a vertical to a diagonal position but the torpedo is held in contact with the object encountered by a spring 26 which is anchored 5 to the base as at 27 and has its opposite end connected to the rack bar 18 near its upper end and therefore when the peg is broken, the spring holds the torpedo in contact with the obstruction and as the obstruction or the 10 vessel moves, the torpedo is dragged over the surface of the obstruction and under ordinary conditions will be fired.

From an inspection of the drawing and from the foregoing description, it will be 15 obvious that the rack bar may be raised or lowered by operating the pinion and it is preferable to disconnect the spring 26 from the rack bar when it is to be elevated. When the said rack bar has been elevated, the gear 20 7 may be rotated for the purpose of oscillating the housing and the rack bar therein so that the rack bar and torpedo holder may be moved from a vertical position as shown in Fig. 1 to the horizontal position shown in 25 dotted lines in Fig. 1 and that a reversal of the operation will replace the rack bar and torpedo holder in the vertical position in which they are illustrated in Fig. 1.

When a torpedo has exploded and the 30 holder is elevated for the purpose of replacing a torpedo, the spring 26 is disconnected from the rack bar, but on restoring the parts to the operative positions, a new peg is placed in the link and rack bar and the

spring is again connected to the rack bar, 35 the normal positions of the said parts.

I claim:

1. In a torpedo holder, a base, a gear wheel rotatably mounted thereon, a housing carried by the gear wheel, a rack bar 40 slideable within the housing, a pinion, a shaft journaled in the gear wheel on which the pinion is mounted, said pinion engaging the rack bar, a pin for holding the rack bar in one position of adjustment and adapted to be sheared when force is applied to the rack bar, means for yieldingly holding the rack bar when released, and means for rotating the gear wheel.

2. In a torpedo holder, a base, a gear 50 wheel thereon, a housing carried by the gear wheel, a bar slideable in the housing, means for reciprocating the bar in the housing, means for holding the bar against movement and adapted to release the bar upon impact 55 of the torpedo, and means for yieldingly holding the rack bar after an impact.

3. In a torpedo holder, a base, a gear wheel thereon, means for rotating the gear wheel, a housing carried by the gear wheel, 60 a rack bar slideable in the housing, means for reciprocating the bar in the housing, means for holding the bar against movement and adapted to release the bar upon impact of the torpedo, and means for yieldingly holding the rack bar after an impact.

BENJAMIN F. SCIFORD.
